UNITED STATES PATENT OFFICE.

AMOS P. STEINER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

HYDRAULIC SELECTIVE INTERNAL GRINDER.

Application filed April 27, 1925. Serial No. 26,232.

My said invention relates to a selective internal grinding machine and it is an object of the same to provide an internal grinder in which either the grinding wheel or the work may be caused to traverse relatively to the other.

Another object is to provide a part of very light weight for rapid reciprocation. The wheel carriage is comparatively small and of 10 light weight, enabling it to make more reciprocations with less power and vibrations, for rapid grinding on short work.

Another object of the invention is to provide means for moving the work support 15 rapidly to a distance from the wheel, as for changing work, with means whereby the rotation of the work is automatically stopped as it retreats from the wheel and automatically restarts as it approaches the position of 20 the wheel.

Another object of the invention is to provide hydraulic operating means for the traverse mechanism of the work carriage and the wheel carriage.

25 A further object of the invention is to provide by one lever, means whereby the work, the work carriage, and the wheel carriage may be stopped and the pressure relieved from the whole system, thereby saving power.

30 Referring to the accompanying drawings which are made a part hereof and on which similar reference characters indicate similar parts,

Figure 1 is a front elevation of my machine in a preferred embodiment thereof,

Figure 2, a similar view, on a larger scale, of the grinding wheel carriage and operating mechanism thereof;

Figure 3, a detail in plan of controlling 40 mechanism for the motor of the traverse means for the grinding wheel carriage,

Figure 4, an end elevation of said means viewed from the right in Figure 2,

Figure 5, a plan view partly in section on line 5—5 of Figure 1 showing speed changing mechanism for the work chuck spindle on the headstock.

Figure 6, a detail of the clutch operating mechanism and parts coacting therewith, and

50 Figure 7, a detail of the clutch shifting levers seen from the right in Figures 1 and 5.

Figure 8 is an end elevation of the machine showing the relative location of the various working parts,

55 Figure 9 is a plan view of the machine.

Figure 10 is a transverse sectional elevation through the plane of rotation of the oscillating motor.

Figure 11 is a sectional plan view of the valve mechanism of the motor for reciprocating the grinding wheel.

Figure 12 is a sectional front elevation of said motor and valve mechanism.

Figure 13 is the same as Fig. 12 with the valve and piston in correspondingly different 65 positions.

Figure 14 is an end elevation of said motor in section.

Figure 15 is a front elevation including the work carriage and the parts mounted 70 on it.

In the drawings reference character 10 indicates a frame of any conventional or desirable character for supporting the various operating elements hereinafter described. 75 A work carriage 11 is mounted for reciprocation on a track on the upper part of the frame said carriage bearing a rack 11' movable by a gear wheel 12' for traversing the carriage to-and-fro. The carriage bears a work supporting spindle or chuck-shaft 12 driven by beveled gears from a shaft 13 similarly driven from a shaft 14 which is mounted for sliding movement through a sprocket 15 driven by means hereinafter described. A 80 rear extension of the frame supports a carriage 16 adjustable toward and from the work in any desirable manner and held yieldably in its forward position by a spring 17, Figure 4. A pulley 18 on this carriage is connected by a belt 19 to a wide-faced pulley 20 on a shaft having a reduced portion 20' which carries a grinding wheel 22, the wide-faced pulley permitting the belt to travel back and forth with the reciprocating carriage for the 85 grinding wheel or other abrading device. The pulley 18 is on the same shaft 21 with a pulley 23 driven by a belt 23' which is driven directly or indirectly from a pulley 24 on the main shaft of the machine or from any other 90 convenient source of power.

A loose pulley 25 (Fig. 5) is driven by a belt 26 which may be connected in any suitable manner with the main shaft or other source of power. The pulley is loose on a 105 shaft 27 and is formed at one end with an internally beveled flange 28 adapted to mate with an externally beveled flange on a part 29 splined to the shaft, the two parts forming a clutch for driving the shaft from the 110

pulley. The clutch member 29 is controlled by the lever 30 having forks 30' (Figs. 5 and 7) engaging the clutch member in any suitable manner. The lever is pivoted at 31 and the clutch members are normally held in engagement with each other by a spring 32. A casing 33 (Figs. 1 and 5) covers the clutch, said casing having a slot for lever 30.

The shaft 27 is connected to a shaft 34 by speed varying means comprising a series of sprockets 35, 36, 37, 38 on the shaft 27 and a series of sprockets 39, 40, 41, 42 on the shaft 34, the sprockets being arranged in series of varying size on the respective shafts with the largest sprocket on one shaft opposite the smallest sprocket on the other shaft, and vice versa, and each pair of sprockets is connected by a sprocket chain. The second series of sprockets may be connected seriatim to the shaft 34 on which they are loosely mounted for progressive speed variation by means of a slideable key 43 pivoted at 44 on a spindle 45 and provided with a spring 46 to force it into engagement with slots in the respective sprockets. The spindle is arranged to be moved endwise by a lever 47 (Fig. 1) having at its free end a stop adapted to co-act with any one of a series of openings in a segment 48. The lever is connected in any suitable manner as by links 49 and 50 to a yoke 51 on the spindle 45 and it will be seen that by moving the lever 47 any one of the series of sprockets 39, 40, 41, 42 may have driving connection with the shaft 34. This shaft is connected by means of a sprocket 52 and a sprocket chain 53 to the sprocket 15 on the shaft 14. This gearing affords a very effective and relatively silent speed-change mechanism for the machine of my invention and is enclosed in a housing comprising a removable plate 54 (Fig. 1) cooperating with the housing 33 to enclose the clutch and the change speed gearing.

The main shaft either directly or by convenient connections drives a pump, indicated at 55, which communicates with a tank 56, at the bottom of the frame 10 of the machine, and is so constructed as to receive all oil running down the inner surface of said frame. The pump forces fluid (preferably oil) through a pipe 56' which communicates with a pipe 57 connected to the relief valve 59 Figure 6 and leads back to the tank by a pipe 58. The relief valve 59 holds the fluid at a constant predetermined pressure by adjusting the tension on the spring 58' by means of the screw 59'. Any oil not being used by the motors depresses the spring and flows back to the tank through the pipe 58.

A pipe 62 leads from the main pipe 57 at the opposite side of the inlet pipe 56' and communicates by means of a horizontal pipe 63 with the valve chamber of a hydraulic motor, the casing of which is indicated at 64 while its operating vane is indicated at 65. Valve

mechanism of any desirable form, e. g. an oscillatory or reciprocating reversing valve controlling oppositely located outlets leading to opposite sides of the vane 65, located at the upper end of the casing controls the operation of the motor, this valve mechanism being controlled by a reversing lever 66 which in turn is operated by dogs 66' and 67' on the traversing work carriage said dogs having abutments 68' adapted to strike against a lug 69' fixed to rock with lever 66. Means for slowing the traverse of the work carriage as it approaches the end of its movement in either direction is indicated at 67 comprising a lever operating a valve 68 for reducing the flow of fluid to the motor. Cams 70' on the dogs are provided with inclined faces to act on the free end of this lever. The dogs are adjustable toward and from each other in well-known manner.

A manually operated valve 69 in the same valve casing serves to regulate the speed of the work traversing motor by restricting the flow of the fluid into the motor, and can also be used to stop the motor when desired; however, stopping the motor is usually accomplished by the action of lever 105 operating upon the by-pass valve as will be hereinafter described.

The reversing lever 66 has a roller 70 at its lower end which when the lever is rocked passes over an abutment 71 adapted to throw the lever to one side or the other of its middle position under certain conditions hereinafter described. The gear wheel 12' is fixed to the shaft of the fluid motor or driven from said shaft by suitable gearing.

Still another branch of the main pipe 57 leads, as shown at 72, to the front side of a valve casing 73, Figs. 2 and 3, which casing is provided with a return pipe 74 at the rear leading to the tank 56. The casing contains a double ended valve 75, which connects with a motor casing 76 by means of a pair of passages 77 and 78. The motor casing is fixed by means of a bracket 80 (preferably integral with the motor casing) to an arm 82 projecting forward from the adjustable carriage 16 and integral therewith. The casing contains a piston 79 connected by a rod 79' to the traversable grinding wheel carriage. A valve 72' in the pipe 72 provides means for regulating the speed and cutting off power from the motor 76 of the wheel carriage and thus stopping the traverse of said carriage. The traversing wheel carriage has V-shaped lateral extensions 81 Figure 4 moving in V-shaped guide grooves on the arm 82. The forward one of said grooves is formed in a detachable side member 83 held in place by screws 84 and spaced from the arm 82 by a plurality of shims 85. When in the operation of the machine the guide grooves for the V-shaped extensions 81 become worn,

giving rise to unevenness or looseness in the

movement of the wheel carriage, such wear may be quickly taken up by removing the screws 84 and the frame member 83, taking out one or more of said shims and replacing 5 the parts, the V-shaped parts exerting a sort of wedging action on each other to take up the wear and lift the wheel-carriage back to its proper level.

For controlling the operation of the motor 10 of the grinding wheel carriage I have provided a post 86 on the carriage projecting upward through a slot 86' in the arm 82 above said carriage (Fig. 3) and a yoke 87 fast on said post with a pair of upwardly projecting 15 arms adapted to engage a rock arm 88 pivoted at 89. The rock arm has a perforated head 90 through which a rod 91 passes, which rod is adjustably connected to the rock arm and forms an operating stem for the valve 20 75. Screws are provided at 92 in said upwardly projecting arms for varying the point of impact of the yoke 87 against the arm 88 and thus varying the length of the stroke of the wheel carriage as well as the position of 25 the carriage at each end of its stroke. A spring-pressed abutment 93 has oppositely beveled faces bearing against a roller on a rock arm 94 rigidly connected to the arm 88, said abutment insuring that the arm will 30 move past its central position carrying with it the motor controlling valve.

For moving the clutch lever 30 to throw the clutch 28, 29 into and out of operation I have provided a lever 95 (Figs. 1 and 6) pivoted at 96 and provided with a cam 97 acting on a roller 98 carried by a yoke 99 said yoke being connected by a rod 100 to the clutch lever 30. A spring 101 is provided for moving the lever in a direction to permit the 40 spring 32 (Fig. 5) to throw the clutch into operation and a cam 102 is provided on the traversing work carriage for moving the lever in the opposite direction whereby the cam 97 is made to act through the parts above 45 enumerated to throw the clutch positively out of action and thereby stop the rotation of the chuck-shaft 12.

The yoke 99 carries another roller 103 co-acting with a cam 104 fixed to a hand lever 50 105 by which the operations of the machine may be controlled manually without regard to the automatic controls described. A lever 61 has on its upper side three faces 106, 107, 108 hereinafter referred to for convenience 55 as notches, with which the rounded lateral projection or roller 109 on the lower end of the hand lever coacts.

In the position indicated in the drawings the valve stem 60 has been depressed, compressing the spring—and opening the valve—thereby releasing the pressure and permitting the fluid to by-pass back to the tank without operating either of the motors 64 and 79, also releasing the pressure to reduce the head on the oil pump 55. In this

position also the high part of the cam 104 engages roller 103 to throw the clutch 28, 29 out of engagement and stop the rotation of the work chuck spindle 12.

In the middle position of the lever with its lug 109 in the notch 107 the cam 104 is moved so far as to permit the clutch members 28 and 29 to engage to rotate the work chuck spindle but the valve 60 has not been closed so that the work carriage is not traversed. The 75 rotation of the wheel being independent of the hydraulically-controlled means said rotation will also continue at this time.

When the hand lever is thrown to the position where the lug 109 engages the notch 106 80 the clutch remains in engagement to rotate the chuck shaft and the valve 60 is closed to cause the flow of fluid from the pump to pass through the various passages leading to the motors thereby bringing the motors into operation. In the machine as shown in the drawings the work carriage will now move to the right until the work comes into operative relation with the wheel. Before this occurs the cam 102 on the carriage will have 85 released the lever 95 which lever otherwise holds the clutch out of engagement while the work-carriage is in retracted position regardless of the position of cam 104. When this lever is released the spring 101 swings it to 90 the right and permits the clutch to go into action and start the rotation of the chuck shaft.

The carriage now continues its travel toward the working position and 68' throws 100 the reversing lever into its central position but in the present embodiment of the invention the spring 110 is located on a movable abutment 111 instead of being held in a fixed position as in previous machines and this abutment is permitted to move down so far that the spring exerts no tension on the abutment 71 so that the lever 66 is not thrown past its central position and the reversing mechanism for the work carriage is not operated. When now the grinding operation on a specific piece of work is completed the operator places his foot on a treadle 112 which acts through a link 113 and a lever 114 to lift the abutment 111 and through the spring 115 forces the abutment 71 yielding against the roller 70 on lever 66 which then is moved past the dead center whereby the carriage reversing mechanism is returned to action in a direction to move the work carriage back to 120 the position shown in Figure 1. It has been explained that the excess of pressure fluid which ordinarily would drive the work carriage, will pass back through the by-pass against the yielding resistance of the valve 60 125 when the motor for the work carriage is out of operation.

If, at any time it should be considered desirable to reciprocate the work carriage as in a case where work of unusual length is to 130

be handled a hook 115 (Fig. 1) pivoted at 116 on the frame of the machine and normally held in the position indicated in the drawings may be moved by the operator to the left 5 under the reduced end of the lever 114. Said hook holds the lever in position to force the spring 110 against the abutment 71 in a manner to cause the lever 66 to move past the dead center at each traverse of the work carriage in either direction whereby the carriage 10 will continue to move back and forth.

It will be seen from the foregoing that the grinding wheel carriage may be reciprocated while the work carriage stands still except 15 for the forward and backward movement respectively at the beginning of operation of such a piece of work and at the end of such operation; that the work carriage may be reciprocated while the grinding wheel carriage 20 stands still; that the grinding wheel shaft and the chuck shaft may be rotated while both carriages are stopped, all said operations taking place under power; and that the work carriage may be traversed manually at will. 25 It is also feasible to interrupt the drive for the grinding wheel independently of any of the other means, the connections from the source of power to the shaft of the grinding wheel for driving it being independent of the 30 other driving connections hereinbefore described.

A feature of importance in the mechanism is that the oil tank is located at the bottom of the frame with exhaust pipes leading to it 35 from the different motors and from the bypass valves. The frame of the machine is closed for the most part so that any leakage will almost inevitably be drained back into the tank and not be wasted on the shop floor, 40 thus eliminating waste and at the same time keeping the oil off the floor. Furthermore all parts of the hydraulic mechanism containing packing, e. g. the pump and the motor for the work-carriage, are directly above 45 the tank, so that all leakage will pass to such tank. This feature is of course applicable to other machines as are various other features described and claimed in this application.

6 Valves for the fluid motors are located in the one instance entirely above the motor and in the other instance above the working parts of the motor. This avoids a difficulty that has been found in the art of fluid motors, particularly in connection with grinding machinery which difficulty arises out of the fact that gas or air or both may occur in the motor, as by generation of gas when the oil becomes heated in the system and accumulates in the motors in a way to interfere with their satisfactory operation causing trembling and irregularity in the operation. By the present arrangement the air or gas which naturally rises to the highest level passes into the valve casing and thence is exhausted with the ex-

haust fluid so as to pass back into the tank whence it can escape into the outer air. This is a feature of great importance in the necessarily delicate and accurate operation of grinding machines, where ponderous machinery must move with the greatest certainty and exactitude. 70

The ordinary operation of the machine may be recapitulated briefly as follows:

With the parts in the position shown in 75 Figure 1 the clutch controlling the chuck shaft is out of action and power is cut off from the fluid motors. The movement of the carriages may now be initiated (preferably after starting rotation of the grinding wheel) by 80 moving the hand lever 105 in a clockwise direction until the detent 109 rests in the notch 106 whereupon the wheel carriage will begin to reciprocate and the work carriage will move to the right, the chuck shaft remaining 85 idle until the cam incline 102 on the work carriage passes the lever 95 whereupon the springs 101 and 32 move the parts into driving relation with the chuck shaft and rotation of the shaft begins. The carriage continues 90 to move forward at a uniform speed until the left-hand cam 70' strikes the free end of the lever 67 and depresses it so as to slow down the carriage movement gradually by closing the valve 69 slowly. The abutment 68' now 95 strikes the lever 66 and moves it into upright neutral position whereupon the carriage stops because of the interruption of the action of its motor. The grinding wheel now operates on the work for such a length of time as 100 may be desired after which the operator places his foot on the treadle 112 and forces the abutment 71 upward to move the lever 66 past the dead center whereupon the action of the motor is reversed and the carriage is 105 moved towards the position shown in Figure 1. When it reaches this position a dog 68' on the carriage strikes the lever 66 and moves it again to neutral position, the grinding wheel carriage still reciprocating and the 110 grinding wheel continuing to rotate. The rotation of the chuck however, has been stopped because of the engagement of the cam 102 and the lever 95.

At this time the lever 105 is in its extreme 115 right hand position. If it should now be desired to bring the work carriage to the right from the position shown in Figure 1, without rotating the chuck shaft the lever 105 is moved to its middle position with lug 109 in the middle notch 107 whereupon the fluid motors will move the carriages but the cam 104 will bear against the roller 103 to hold the clutch of the chuck shaft positively 120 out of operative position.

If the lever is moved to the position shown in Fig. 1 the fluid by-pass through the valve 59 is opened and both fluid motors remain stationary whereupon the carriages may be 125 adjusted in various respects and moved to 130

ward and from one another in a manner familiar to those skilled in the art, the rotation of the grinding wheel continuing unless interrupted by manipulation of parts not shown in the drawings.

It will be obvious to those skilled in the art that the device may be modified in many respects without departing from the spirit of the invention and therefore I do not limit myself to what is shown in the drawings and described in the specification but only as indicated in the appended claims. An important feature of my invention is the light weight wheel carriage which is adapted for very rapid reciprocation throughout the entire stroke or nearly so and being followed by a quick reversal in the direction of movement. This is important in that it makes for high speed of operation.

Having thus fully described my said invention what I claim as new and desire to secure by Letters Patent is:

1. A grinding machine comprising a frame, a grinding wheel, means for reciprocally traversing said wheel, a reciprocably mounted work carriage, means for traversing said carriage through a range beyond that of the reciprocating wheel including a lever movable to control and reverse said traversing motion to move said lever and stop said traversing motion, and normally inoperative manually controlled means to further move said lever to reverse the traversing motion, substantially as set forth.
2. A grinding machine comprising a frame, a grinding wheel, fluid pressure means for reciprocally traversing said wheel, a reciprocably mounted work carriage, means for traversing said carriage through a range beyond that of the reciprocating wheel including a lever movable to control and reverse said

traverse, means controlled by said traverse motion to move said lever and stop said traversing motion, and normally inoperative manually controlled means to further move said lever to reverse the traversing motion and means operative near the end of each traverse of the carriage for slowing down the traversing motion, substantially as set forth.

3. A grinding machine having a bed or track and a work carriage reciprocable longitudinally thereof and a grinding wheel carried by a shaft substantially parallel to said bed, a carriage movable transversely of said bed having an arm extending forward over said bed and upon which the grinding shaft is mounted so that it may be brought into line with the travel of the work and may travel axially, and means for traversing said grinder shaft axially comprising a directly connected fluid pressure cylinder and piston mounted on the forwardly extended arm, substantially as set forth.

4. A grinding machine comprising a base, a work carriage reciprocable longitudinally thereof, a grinding wheel base movable transversely of the base, the said grinding wheel base having an arm extending forwardly and upwardly therefrom and having a cylinder mounted within said extended arm, a piston within said cylinder, a grinding wheel mounted upon said piston, fluid pressure means for reciprocating the said piston, and means for adjusting the range through which the said piston reciprocates, substantially as set forth.

In witness whereof, I have hereunto set my hand at Waynesboro, Pennsylvania, this 23d day of April, A. D. nineteen hundred and twenty-five.

AMOS P. STEINER.
